Mfg. Co., Streator, Ill., a corporation of Illinois

Application October 27, 1942, Serial No. 463,485

8 Claims. (Cl. 5—237)

This invention relates generally to furniture and in particular to an article of furniture of a construction for yieldably supporting a person thereon.

Furniture such as chairs, cots, beds and the like for yieldably supporting a person thereon, namely, yieldable to the weight of a person to resiliently support him, are well known in the prior art. This type of furniture is generally constructed in large part of metal, with the yielding or resilient structure comprising metal springs, flat frame steel members, or spring arms supported at one end with the other end free to bend down when a weight or force is applied thereon. Although these prior art structures are generally satisfactory their substantially all metal construction makes them relatively expensive. Further they are usually of a permanent assembly so as to prevent their being collapsed into a compact package for carrying to the place where they are to be used.

It is an object of this invention, therefore, to provide an improved article of furniture for yieldably supporting a person thereon.

A further object of this invention is to provide yieldable furniture such as a chair, cot, bed or the like which does not require any metal in the general construction thereof but which has all of the normal resiliency of metal spring furniture.

Another object of this invention is to provide furniture of a non-metal construction adapted to yieldably support a person thereon, which is of a sturdy and compact design, inexpensive in cost, restful and comfortable in use, and which readily fits itself to the contour of the user.

A feature of this invention is found in the provision of an article of furniture having a fabric portion extended between oppositely disposed side portions of the article for yieldably supporting a person thereon, in which wooden spring members are bowed between the side portions to extend the fabric portion and yieldably retain the side portions in an assembly relation. On support of a person on the fabric portion, the same is yieldably depressed against the spring pressure of the wooden members acting against the side portions.

Still another feature of this invention is found in the provision of a non-metal article of furniture for yieldably supporting a person thereon, which is of a collapsible type and has main and auxiliary wooden spring members, for retaining the article in a supported position, adapted to be manually sprung between rigidly constructed side

portions of the article to reduce the assembly costs thereof.

Another feature of this invention is found in the provision of a non-metal constructed article of furniture for yieldably supporting a person thereon, in which a fabric supporting portion is associated in the frame structure of the article with wooden spring members so as to be capable of being yieldably depressed after it has been completely extended or stretched.

A further feature of this invention is found in the provision of a non-metal constructed article of furniture for yieldably supporting a person thereon, in which rigid side portions are yieldably connected by means including a fabric supporting portion and wooden spring means to provide for such supporting portion being yieldably depressed after it has been completely extended or stretched.

Further objects, features, and advantages of this invention will become apparent from the following description taken in connection with the accompanying drawings in which:

Fig. 1 is a rear perspective view of a chair constructed according to this invention;

Fig. 2 is a transverse sectional view of the chair in Fig. 1 showing the assembly relation of a fabric seat portion and wooden spring members with the side members thereof;

Fig. 3 is a view illustrated similarly to Fig. 2 showing the fabric portion and spring wooden members in changed position;

Fig. 4 is a fragmentary sectional view as seen along the line 4—4 in Fig. 2 showing the construction and relative arrangement of the wooden spring members;

Fig. 5 is a top perspective view of a cot or bed of this invention; and

Fig. 6 is a transverse sectional view taken along the line 6—6 in Fig. 5.

The invention is illustrated in the drawings as applied to a chair and a bed. It is to be understood, however, that it is not to be so limited and may be applied to any kind of furniture adapted to yieldably support a person thereon, such as a rocker, an easy chair, a davenport and the like. An article of furniture, made according to this invention, includes a pair of vertical oppositely disposed side structures of a rigid construction.

A fabric material, such as canvas or the like, constitutes a supporting portion for the user of the furniture and is tacked or otherwise secured to corresponding portions of the side structures so as to be extended therebetween when the side structures are spaced apart from

each other. This spacing apart of the side structures is accomplished by wooden spring members of a flat form, which are sprung or bowed between the side structures to apply a pressure outwardly thereon, with the spacing of the side structures being determined by the extension of the fabric portion therebetween. Some of the spring members are located in a horizontal plane below the fabric portion, while others of the spring members are located above the fabric portion in a plane substantially normal to the plane of the first spring members. The spring members thus cooperate with the fabric portion to yieldably connect and retain the side structures in an assembly position while providing for a yieldable depressing of the fabric portion when a person is supported or applies a force thereon. Any twisting movement of the side structures out of an aligned assembly position is prevented by virtue of the fact that certain of the wooden spring members are relatively wide with the ends thereof positioned in corresponding grooves in the side structures. Each end of these wooden spring members thus extends over a considerable portion of a corresponding side structure for abutting engagement therewith so as to eliminate any tendency of the side structures to pivot about the ends of the spring members and out of a plane substantially normal to the spring members.

Referring to the drawings there is shown in Fig. 1 a chair having a pair of side structures 10 each of which structures includes a front leg 11, a combination rear leg and back support 12, and a connecting member 13 rigidly connected with the front and rear legs. A piece of fabric material 14, such as canvas or the like, is tacked or otherwise suitably secured to the connecting members 13 and is extended between the side structures 10 to constitute a seat portion for the chair. The inner side of each connecting member 13 is provided with a longitudinal groove 16 (Figs. 2 and 3) which is arranged below the seat portion 14. Main wooden spring means 15 comprising a plurality of individual slats 17 are sprung between the side structures 10 and bowed or bent downwardly from the seat portion 14. Each end of a slat 17 is loosely received in a corresponding groove 16, with the bowing of the slat members placing them under an initial tension to apply a force or pressure outwardly on the side structures 10 to urge the same apart a distance defined by the extension or stretching of the fabric seat portion 14.

The back supporting portions 18 of the rear legs 12 have a fabric material tacked thereto to form a back portion 19 for the chair. Each leg portion 18, rearwardly of the back portion 19, is formed with a substantially vertical groove 21 to receive therein main wooden spring means 22 which is of a construction similar to the spring means 15. The spring means 22 is bowed outwardly from the back portion 19. It is seen, therefore, that the spring means 22 is arranged in a plane substantially normal to the spring means 15 and above the level of the seat portion 14. Thus the action of the wooden springs 15 to move the back supporting portions 18 inwardly toward each other is counteracted by the action of the wooden springs 22 urging the corresponding opposite pairs of legs 11 and 12 toward each other. These actions of the spring means 15 and 22 to spread the side structures 10 apart from each other is limited by the extension or stretching to a taut position of the fabric seat portion 14 and the fabric back

portion 19. The side structures 10 are thus yieldably connected against collapse and retained in an assembly position by the cooperating assembly of the spring means 15 and 22 and the fabric portions 19 and 14.

Because of this yieldable connection of the side structures 10 any force or weight applied on a fabric portion 14 or 19 yieldably depresses the same toward a corresponding spring means 15 and 22 as is indicated in Fig. 3 for the fabric or seat portion 14. Since the spring means 15 is bent or bowed in a direction away from the seat portion 14 the application of a weight on the seat portion tends to further bend the spring means 15 away from the seat portion. Thus, regardless of the weight supported on the seat portion 14, a clearance will always be maintained between the seat portion and the spring means 15 so that at no time does the seat portion engage the spring means. As a result the seat portion is yieldably depressed to resiliently support any weight carried thereon. The operation of the spring means 22 and back portion 19 is similar in all respects to the operation of the seat portion 14 and the spring means 15 so that a further description thereof is believed to be unnecessary. It is apparent, of course, that the depressing of the seat portion 14 downwardly and of the back portion 19 rearwardly tends to move the side structures 10 away from each other at the bottom. However, the tension of the spring means 15 and 22 is such as to limit this movement to a minimum without impairing the yieldable function of the seat portion 14 and back portion 19.

As explained above the main spring means 15 and 22 are each comprised of individual slat members. This construction of the spring means, although providing for the resilience or yieldability of the portions 14 and 19, does not entirely prevent twisting of the chair frame resulting from a rocking of the chair from side to side, or on its back legs, or from the application of a force on the chair in any direction tending to move the side structures out of their normal oppositely disposed and aligned relation. In order to maintain the normal assembly relation of the side structures 10, regardless of the torsional forces applied on the chair tending to twist the same, there is provided an auxiliary or supplementary wooden spring means 23 and 24 corresponding to each of the main spring means 15 and 22, respectively. Each auxiliary spring means 23 and 24 is of a like construction and similarly assembled with a corresponding main spring means. Only the auxiliary spring means 23, therefore, will be described in detail.

The auxiliary spring means 23 (Figs. 2 and 3) is formed of a single panel coextensive in width with the main spring 15 and located adjacent thereto with its ends positioned in the grooves 16. A separate groove may be provided in the connecting members 13 to receive the auxiliary spring means 23, but this would necessitate an additional machining operation, and in turn an increase in the cost of the chair. The single panel comprising the auxiliary spring means 23 is somewhat longer than the slats 17 comprising the main spring means 15 so that on a bowing thereof between the side structures 10, the bend therein is greater than the bend in the members 17. The auxiliary spring means 23 is thus of a corresponding contour with the main spring means 15 but is spaced therefrom over its bowed portion as is clearly indicated in Figs. 2 and 3. By virtue of the one piece construction of the spring

means 23, wide engaging surfaces are provided at the ends thereof for abutting engagement with the side structures 10 over substantially the complete length of the grooves 16 in the connecting members 13. These wide engaging surfaces eliminate any tendency of the side structures 10 to pivot about the ends of the auxiliary spring means 23 and out of a plane substantially normal to the spring means 23. As a result of this function of the spring means the side structures are retained against any relative movement in a direction from front to back of the chair. Since the auxiliary spring means 24 is in a plane substantially normal to the spring means 23, it acts to prevent any relative movement of the side structures in an up and down direction. The spring means 23 and 24 thus cooperate to retain the side structures in their oppositely disposed assembly relation against any twisting forces which might be applied thereon.

Although the auxiliary spring means 23 and 24 function to prevent any torsional strains or twisting action between the component parts of the chair they also act to reinforce the main springs 15 and 22, respectively, to extend the canvas supporting portions 14 and 19, respectively. This double action provides greater flexibility or yieldability over an entire range of forces than can be accomplished by the use of a single spring means capable of counteracting the strongest force applied on the canvas portions and tending to depress the same. In one embodiment of the invention the wooden slats 17 comprising the main spring means 15 and 22 are about $\frac{1}{6}$ " thick and $1\frac{1}{2}$ " wide, with a corresponding auxiliary spring means 23 and 24 having a thickness of about $\frac{3}{28}$ " and a width substantially coextensive in length with the grooves 16 in the connecting members 13. It is to be understood that both the main and auxiliary spring means may be of a laminated construction, with the assembled laminations having the same dimensions as the single pieces above explained. These dimensions, of course, are variable with various types of chairs, with lighter or fewer springs being used for an ordinary chair as compared to a lounging chair or the like. Because of the relatively small thicknesses of the main and auxiliary spring means and their free insertion within the grooves in the side structures 10 they may be manually bowed and assembled relative to the side structures 10 whereby to eliminate the use of any machines in the assembly of the chair and in turn reduce its overall cost. Further the manual assembly provides for the chairs being shipped and sold directly as a collapsible kit or unit which can be easily assembled by the user thereof.

As mentioned above a single spring means may be used in place of each combination of main spring means and auxiliary spring means described. The single spring means would comprise a panel member similar in all respects to a panel member forming the auxiliary spring members 23 and 24, but having a thickness equal substantially to the combined thicknesses of the main and auxiliary spring means 15 and 23, or 22 and 24, respectively. A single spring means of this design would thus operate to perform the functions of both a main spring means and a corresponding auxiliary spring means.

The application of the invention to a cot or bed is shown in Figs. 5 and 6. The cot includes a pair of side structures 26 comprising head and foot portions 27 and 28 rigidly connected to a

connecting member 29. A fabric portion 31 is attached to the connecting members 29 and extends between the head and leg pieces 27 and 28 and between the side structures 26 to form a support for the user of the cot. The spring construction comprises a main spring means 32 including a plurality of slats 33 bowed downwardly from the canvas portion 31 and arranged in a spaced relation longitudinally of the connecting members 29, with the ends of these slat members being freely receivable in a corresponding longitudinal groove 34 formed in the connecting members 29. Since most of the weight on a cot is supported toward the head thereof the slats 33 may be more concentrated at the middle and head portions thereof. An auxiliary spring means 36 is comprised of a pair of panel members 37, one near the head and one near the foot of the cot, which cooperate to prevent any twisting movement of the side structures 26 in a direction longitudinally of the cot. There is not as great a tendency in the side structures 26 being moved longitudinally relative to each other, as contrasted to the side structures 10 of the chair in Fig. 1, so that a single panel having a width equal to the length of the bed is not necessary. The auxiliary spring means is also bent downwardly from the fabric portion 31 with the bow therein spaced from the bowed portion in the main spring means 32, it being understood that the ends of the panels 37 are carried in the grooves 34.

To counteract the outward pressure of the spring means 32 and auxiliary spring means 36 to extend the fabric portion 31 and to move the oppositely corresponding upper portions 38 and 39 of the head and foot pieces 27 and 28, respectively, toward each other, there is provided end springs 40 and 41 at the head and foot of the bed, respectively. The opposite foot portions 39 and head portions 38 are each provided with a groove 42 in the inner side thereof for receiving therein the ends of a corresponding spring member 40 and 41. In one embodiment of the invention each spring means 40 and 41 is about $\frac{1}{4}$ " thick by 10" wide, and may be constructed of either a single panel or a laminated construction of like overall dimensions. As shown in Fig. 5 the springs 40 and 41 are sprung between the side structures 26 with each thereof being bowed outwardly from a corresponding end of the bed. The action of the main spring means 32 and auxiliary spring means 36 is believed to be entirely clear from the description of the action of the main and auxiliary spring combinations in the chair of Fig. 1. The side structures 26 are thus completely yieldably connected together to provide for a desired yieldability of the canvas portion 31 when the bed is used. Thus on a depressing of the canvas portion 31 the springs permit a yieldable moving of the side structures 26 away from each other at the bottom, with this movement being restricted within desired limits by the construction of the springs.

From a consideration of the above description, therefore, it is seen that the invention provides an article of furniture for yieldably supporting a person thereon, in which yieldability is accomplished by the cooperative assembly of wooden spring members removably connected, in the assembly of the furniture, to yieldably retain the side structures thereof against collapse while providing for the yieldable depressing of a fabric portion for carrying the user of the furniture.

This removable connection of the wooden spring members provides for the article of furniture being readily knocked down or assembled to permit its ready transportation from place to place. Main and auxiliary wooden springs are used to increase the resiliency of yieldability of the canvas supporting portion over a wide range of forces to be applied thereon, and by virtue of their relative dimensional sizes are adapted to be completely manually assembled so as to eliminate the need of machines in the assembly operation and reduce the overall cost of the furniture. Although the spring structures are located adjacent to the fabric supporting portion, they are bent or bowed in a direction away therefrom so that on the application of a weight or a force on the fabric portion, this bending is increased in a direction away from the fabric portion so that the springs and fabric portions are always spaced from each other. Thus at no time in the use of the furniture is the user thereof supported directly on the wooden spring members so that the fabric portion is completely yieldable between predetermined design limits. Further, since the canvas supporting portion is connected only to the side structures of the article of furniture complete yieldability thereof is provided at both ends of the furniture due to the elimination of rigid connecting members transversely of the furniture. Thus with particular reference to the chair in Fig. 1 it is seen that the fabric portion 14 at the front of the chair is entirely yieldable so that the legs of the user yieldably depress the fabric portion concurrently with the depression of the remaining surface of the canvas portion. A stiff support across the front of the chair which would prevent any yielding at this portion is thus entirely eliminated so as to increase the overall comfort of the chair. The side structures and spring members of the furniture are adapted to be formed from commercially available dimensioned pieces of wood material, with the machining thereon to provide for their assembly in a complete frame structure being easily and readily formed by simple machining operations.

Although the invention has been described with reference to several preferred embodiments thereof it is to be understood that it is not to be so limited since modifications and alterations can be made therein which are within the full intended scope of the invention as defined by the appended claims.

I claim:

1. An article of furniture including a pair of upright side structures, foldable means connected to said side structures and extended therebetween to form a body supporting portion, means cooperating with said foldable means to yieldably retain said side structures in said oppositely disposed relation including flat bendable members arranged in a bowed position between said side structures to urge the same apart, and other flat bendable members bowed between said side structures and having the ends thereof in abutting engagement with said side structures and of a size to normally prevent movement of said side structures out of a plane substantially normal to said first named members, with the support of a body on said supporting portion yieldably depressing the same against the pressure exerted on said side structures by said first named members.

2. An article of furniture having a pair of upright side structures, foldable means connected

with said side structures and extended therebetween to form a body supporting portion, means for extending said foldable means to a body supporting position and cooperating with said foldable means to yieldably retain said side structures against collapse including a plurality of flat bendable wooden members arranged in a bowed position between said side structures, with at least two of said flat members being in planes substantially normal to each other, with one thereof below the level of said supporting portion, and the second thereof above the level of said supporting portion, other bendable wooden members arranged in a bowed position between said side structures adjacent said body supporting portion, but bent downwardly therefrom, with the support of a body on said supporting portion yieldably depressing the same against the action of all of said bowed wooden members on said side structures.

3. An article of furniture for yieldably supporting a body thereon including a pair of upright side portions, fabric means extended between said side portions for supporting said body thereon, main wooden spring means of flat form arranged in a bowed position between said side structure, with said main spring means applying a pressure outwardly on said side structures to extend said fabric means and cooperating with said fabric means to yieldably retain said side structures against collapse from their upright positions, and flat auxiliary wooden spring means bowed between said side structures, with each end of said auxiliary spring means being relatively wide and in abutting engagement with a corresponding side structure to prevent any twisting of said side structures out of a plane normal to said auxiliary spring means, with the support of a body on said fabric means yieldably depressing the same against the action of said main wooden spring means on said side structures.

4. A chair having a pair of rigidly constructed upright side portions, with each side portion including a front leg and a back leg with a connecting portion therebetween, fabric means connected to said connecting portions, with each connecting portion having a horizontal groove therein, and each back leg having an upright groove therein above the level of a corresponding connecting portion, other fabric means connected to said back legs adjacent the upright grooves therein, and wooden spring members of flat form having the ends thereof received in corresponding upright and horizontal grooves in said side portions and arranged in a bowed position to urge said side portions away from each other to extend said fabric means therebetween, with the application of a force on said fabric means yieldably depressing the same against the pressure of said spring members on said side portions.

5. A cot having a pair of upright side portions of rigid construction, with each of said side portions including a longitudinal member with a leg at each end thereof, fabric means attached to said longitudinal members and extended between said side portions, each longitudinal member having a horizontal groove therein and each leg having a vertical groove therein at a level above said longitudinal members, wooden spring members of flat form having the ends thereof received in opposite corresponding grooves in said legs and connecting portions, said spring members being in a bowed position to urge said side portions apart and extend said fabric means to a body supporting position, with said wooden

spring members cooperating with said fabric means to prevent the collapse of said side portions and retain the same against movement out of a plane normal to said spring members, with the support of a body on said fabric means yieldably depressing the same against the spring action of said wooden members on said side portions.

6. An article of furniture including a pair of rigidly constructed upright side portions, with each of said side portions including a pair of legs and a connecting portion therebetween, fabric means extended between said side portions at said connecting portions for supporting a body thereon, flat wooden spring members arranged in a bowed position between said side portions and engageable therewith to urge the same apart and to extend the fabric means to a body supporting position, with certain of said wooden spring members being positioned between said connecting portions, and other of said wooden spring members being positioned above the level of said connecting portions and between corresponding opposite legs of said side portions, with said certain and other wooden spring members cooperating with said fabric means to yieldably retain said side portions against collapse, with support of a body on said fabric means yieldably depressing the same against the spring action of said wooden spring members on said side portions.

7. An article of furniture comprising a pair of upright side structures, each of said structures including a longitudinally extending mem-

ber having an upright leg at each end thereof, foldable means extending between and attached to said longitudinally extending members, flat spring members having their ends respectively

5 anchored at said longitudinally extending members, said spring members being bowed to urge said side structures apart and thus extend said foldable means to a body supporting position, and yieldable spring means connected between at least two of said legs to resist the thrust exerted by said flat spring members on said longitudinally extending members while permitting relative movement between said structures when said foldable means is flexed by body pressure

15 exerted thereon.

8. An article of furniture for yieldably supporting a body thereon including a pair of upright side structures respectively provided with corresponding elongated parts, foldable means extending between and connected to said elongated parts to support a body thereon, relatively narrow flat spring members extending between said elongated parts and arranged in bowed positions to urge said side structures apart and thus extend said yieldable means to a body supporting position, and a wide flat auxiliary spring member extending between said elongated parts to resist relative longitudinal movement between said elongated parts, said auxiliary spring member being bowed to permit relative lateral movement between said side structures.

DAVID M. POPE.
